UNITED STATES PATENT OFFICE

JOSEPH BOROVITZ, OF NEW YORK, N. Y., ASSIGNOR TO JOSEPH BOROVITZ, INC., OF NEW YORK, N. Y., A CORPORATION OF NEW YORK

DESIGN FOR A COMBINATION RECEPTACLE FOR SMOKERS' ARTICLES OR SIMILAR DEVICES

Application filed August 2, 1929, Serial No. 32,283, and in Germany May 21, 1929. Term of patent 3½ years.

To all whom it may concern:

Be it known that JOSEPH BOROVITZ, a citizen of the United States and resident of New York city, in the county of New York and State of New York, has invented a new, original, and ornamental Design for a Combination Receptacle for Smokers' Articles or Similar Devices, of which the following is a specification, reference being had to the accompanying drawing forming part thereof, in which,

Fig. 1 is a perspective view of a combination receptacle for smokers' articles, or similar devices embodying my new design; and Fig. 2 is a plan view thereof.

I claim:

The ornamental design for a combination receptacle for smokers' articles, or similar devices as shown.

Dated New York city, July 30, 1929.

JOSEPH BOROVITZ.
